US00D769074S

(12) **United States Design Patent** (10) **Patent No.:** **US D769,074 S**
(45) **Date of Patent:** **** Oct. 18, 2016**

(54) **TRIPLE TIER RACK**

(71) Applicant: **Pretty Star Store LLC**, Rowland Heights, CA (US)

(72) Inventor: **Tsung-Yu Tsai**, Changhua (TW)

(73) Assignee: **PRETTY STAR STORE LLC**, Rowland Heights, CA (US)

(**) Term: **14 Years**

(21) Appl. No.: **29/518,040**

(22) Filed: **Feb. 19, 2015**

(51) LOC (10) Cl. **07-06**

(52) U.S. Cl.

(57) **CLAIM**

The ornamental design for a triple tier rack, as shown and described.

DESCRIPTION

FIG. 1 is a perspective view of a triple tier rack showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures represent portions of the triple tier rack that form no part of the claimed design.

1 Claim, 5 Drawing Sheets
